UNITED STATES PATENT OFFICE.

LUIS AIMÉ, OF WEST HOBOKEN, NEW JERSEY.

LEG REST FOR ROCKING-CHAIRS.

1,412,641.

Specification of Letters Patent. Patented Apr. 11, 1922.

Application filed August 15, 1921. Serial No. 492,311.

To all whom it may concern:

Be it known that I, LUIS AIMÉ, a citizen of the United States, and a resident of West Hoboken, in the county of Hudson and State 5 of New Jersey, have invented a new and Improved Leg Rest for Rocking-Chairs, of which the following is a full, clear, and exact description.

This invention relates to leg rests for rocking chairs and has for an object to provide 10 a construction wherein a rest is provided which will oscillate or rock in time relationship with the rocker.

Another object of the invention is to provide 15 a leg rest for rockers which is always properly held in position but which may be adjusted for different sized persons and when adjusted will act in the usual manner.

A still further object of the invention is 20 to provide a leg rest and means for connecting the same with a rocker which is both foldable and adjustable whereby the rest may be adjusted toward and from the rocker when in use and when not in use may be 25 folded to a position beneath the rocker in order that the rocker may be used in the usual manner of rockers.

In the accompanying drawing—

Figure 1 is a side view of a rocker and 30 rest disclosing one embodiment of the invention.

Figure 2 is a top plan view of the structure shown in Figure 1, certain parts being 35 broken away and shown in section for better illustrating the detail construction.

Figure 3 is an enlarged fragmentary vertical sectional view through the lower part of the rocker and rest when the rest is folded beneath the rocker.

Figure 4 is an enlarged sectional view 40 through Figure 1 approximately on line 4-4.

Figure 5 is a bottom plan view of the 45 bracket as placed under the seat of the chair in Figure 1, and

Figure 6 is a cross sectional view of the parts indicated in Figure 3 and taken along the line 6-6 in the direction of the arrows.

Referring to the accompanying drawing 50 by numerals, 1 indicates a rocking chair of any desired kind provided with a bracing spindle or rod 2 used in connecting the rockers. Associated with the chair 1 is a rest 3 connected with the chair 1 by an upper connection 4 and a lower connection 5

whereby the chair and the rest may act as a single supporting unit. The rest 3 is provided with a pair of side standards 6 which may have any desired shape but which are formed with rocking surfaces 7 at the lower 60 end while at the upper end pivotal rods 8 extend through the standards and through suitable depending brackets 9 projecting from the supporting pad. Immediately below the rod 8 is a second rod or pin 11 extending through the end of hook 12 whereby when the parts are folded under the chair 1 the pin 11 may pass beyond the supporting bracket 13 and thereby allow the pad 10 to come beneath the bottom of the chair 1. 65 The hook 12 forms part of the bar 14, which bar is preferably divided for almost its full length into two longitudinal sections or plates so as to accommodate the link 20 when the parts are folded as shown in Figure 70 75. By dividing the bar 14 in this manner, the clamping screw 19 may also freely operate. The one end of the bar 14 slidably fits into a square tubular member 15, which tubular member accommodates the clamping screw 19 and which at its end is provided with a hook 17 formed by the notch or depression 18 whereby the tubular member 15 may fit over the bracket 13 and be held 80 against accidental movement in either direction.

In order to positively lock the tubular member 15 in engagement with the bracket 13, a locking plate or bar 16 is provided which is shown as being pivotally mounted 90 and clamped in place by a suitable set screw but if desired, it may be a sliding bolt or some other convenient form of fastening means. By reason of the telescopic arrangement of the bar 14 and tubular member 15, 95 the effective length of bar 14 and tubular member 15 may be adjusted and locked or clamped rigidly in any adjusted position for holding the pad 10 any desired distance from the chair 1.

When a person of a certain size uses the device, the parts may be arranged as shown in Figure 1. In case a larger person uses the device, set screw 19 is loosened and rod 14 is pulled out the desired distance and then set screw 19 is again tightened. The link 20 is also moved outwardly so that the pin 2 will fit into the next notch 21 so as to hold the standards 6 normally in a vertical position. The link 20 is pivotally connected 100 105 110

- at 22 to a second link 23, said link 23 having a bent over portion forming a shoulder 24 engaging link 20 and the notch 25 whereby the links may be folded only in one direction.
- 5 Link 23 is formed with an opening at the end opposite the pivotal connection 22 and said opening accommodates the rod 26 which extends through the lower part of the standards 6 whereby the lower part of the rest 10 3 is properly held in place while the upper part is held in place by members 14 and 15 and associated devices. In order to prevent the link 23 from shifting longitudinally of the rod 26, sleeves 27 and 28 are loosely mounted on this rod and extend from near the link 23 to the respective standards 6. When it is desired to fold the rest in order to move the same from the position shown in Figure 1 to that shown in Figure 3, the links 20 and 23 are swung upwardly at a central point, namely, at the pivotal point 22. This will bring the lower end of the standards 6 and associated parts inwardly toward the chair. The connecting structure 4 is then lifted until the tubular member 15 is out of engagement with the bracket or support 13 whereupon the parts may be forced directly toward the chair and the lower part of the standards 6 may be swung upwardly until the tubular members 27 and 28 rest on the supporting arc-shaped arms 29 and 30. These arms are rigidly secured to the chair 1 and act as a support for the lower end of the rest when the rest is folded. After these rollers have engaged the arms 29 and 30 the rest, together with the rod 14, is forced inwardly until the end of the hook 12 strikes the bracket or support 13. When this happens, the parts have assumed the position 40 shown in Figure 3 where they remain until manually removed. When the links 20 and 23 are moved upwardly during the folding action, the movement is continued until the pivotal point 22 rests against the rod 11 and 45 between the side plates or sections of bar 14. The lower ends of the standards 6 are swung upwardly and, consequently, will move or swing the links 20 and 23 upwardly so that they will be almost entirely nested in the 50 space between the sections or side plates of bar 14. After this upward swinging movement has taken place, the parts are forced into position as shown in Figure 3 and heretofore described.
- 55 When the parts are folded the chair 1 may be used as an ordinary rocking chair. When it is desired to again use the foot rest, the parts may be moved outwardly until they assume the position shown in Figure 1 and 60 if desired, the parts could be adjusted to move the same further out or inwardly a short distance. When the rest is in use, it will rock back and forth in unison with the rocker 1

and thereby give not only a proper support to the legs of a person but will permit a natural back and forth movement without any scraping action.

What I claim is:—

1. The combination with a rocking chair of a foot rest comprising a plurality of standards, a supporting member arranged on top of said standards, a pair of links pivotally connected with the standards at the lower end, one of said links having elongated openings merging into an entrance notch, a rod connected with said rocking chair adapted to be fitted into said opening whereby as the rest rocks the links may slide a sufficient distance to take care of said rocking motion, and an adjustable connecting structure having a hooked end connected with the upper part of said rest and with the rocker immediately below the seat whereby the rest may be positioned a sufficient distance from the rocker and continue to function in the proper manner, and whereby the rest may be suspended from the rocker when folded.

2. In combination, a rocking chair having a cross bar at the middle of its runners, a rocking leg rest comprising a pair of standards spaced from each other and mounting a pad at the upper end thereof, a rod extended between and secured to the lower portion of said standards, a plurality of roller tubes enveloping said rod, a bendable spacing member pivoted at one of its ends to said rod between sections of said roller tubes and detachably connected at the other end thereof to said cross bar, and a plurality of arc shaped arms under the seat of said chair for supporting the lower end of said seat when folded, said roller tubes engaging said arc shaped arms.

3. In combination, a rocking chair and a rocking leg rest, a pair of arc shaped supporting members secured under the seat of the chair, a bendable connecting rod pivotally secured to the lower end of the rest and detachably secured to the runners of the chair, an adjustable connecting member pivoted to the upper end of the rest and detachably secured to the lower face of the chair seat, said adjustable member comprising a pair of bars bent into a hooked portion at the pivoted end, and a detachable tubular bifurcated member provided with securing means adapted to receive said bars, said rest being adapted to be supported under the chair seat when not in use by means of said arc shaped supporting members and said hooked portions of said bars, said bendable connecting rod nesting between said bars when the rest is folded.

LUIS AIME.
